UNITED STATES PATENT OFFICE.

JAMES A. SHEPARD, OF MONTOUR FALLS, NEW YORK, ASSIGNOR TO SHEPARD ELECTRIC CRANE & HOIST COMPANY, OF MONTOUR FALLS, NEW YORK, A CORPORATION OF NEW YORK.

CRANE BRIDGE.

Application filed September 16, 1927. Serial No. 219,958.

The general object of the present invention is to provide an improved crane bridge characterized by its mechanical simplicity and by the manner in which the strength and rigidity required to withstand the stresses to which the structure is subjected, is secured with a bridge structure lighter in weight and simpler in form than has heretofore been required under similar conditions of use. More specifically, the object of the invention is to provide a travelling crane bridge having its main beam or girder elements so reinforced and supported to withstand stresses tending to bend and twist said elements that the latter may each be formed of a single I beam or channel bar for use under conditions which have heretofore required such beams to be composite or box girders.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is a somewhat diagrammatic plan view of an overhead travelling crane structure;

Fig. 2 is a perspective view of a portion of the bridge structure; and

Fig. 3 is a partial section on the line 3—3 of Fig. 1.

The travelling crane structure shown somewhat diagrammatically in Fig. 1, comprises a bridge composed of two main girder elements A connected at their opposite ends to crane and frame members B in which are journalled the bridge supporting wheels C which run on rails D' carried by stationary supports D. The crane is propelled along the rails D' by a motor E located at one side of the space between the girder A and secured to the side of one of the latter. The tops of the girders A serve as, or as shown, support track rails a for the supporting wheels of a trolley F on which is mounted the motor driven hoist f, and the motor for propelling the trolley along the rails a. G represents a depending operator's cage which

ordinarily, and as shown, depends from the bridge structure at one side of the space between the girders A and is supported wholly by one of the latter or partly by one of the latter and by one of the end frames of the bridge. Ordinarily, and as shown, there is a walkway g' running alongside the girder A at the side of the bridge at which the cage G is located.

In so far as already described, the construction shown in Fig. 1 represents the usual and regular practice of the prior art. In such a crane structure the girders A must not only be strong enough and stiff enough to safely support the maximum static load imposed by their own weight and the weights of the parts carried by them including whatever weight may be suspended from the hoist f on the trolley F, but must have strength and stiffness to prevent significant bending or twisting of the girders. The bending and torsional stresses to which the girders are subjected are relatively large, and arise from various causes. Of these causes the one ordinarily most important is the reaction on the bridge of the means for propelling the bridge along the rails D'—the torque of the armature of the motor E subjecting the frame of that motor to an opposing torque. The weight of the bridge propelling means, the walkway g' and the cage F all of which are ordinarily located at one side of the space between the beams A to provide clearance for the hoist chain or chains, subjects the girder A by which they are supported, to substantial torsional stresses. Furthermore, the starting and stopping of the crane in its movements along the track rails D' subject the girder to inertia and momentum effects tending to deflect the latter horizontally.

In accordance with the present invention, each main girder A, shown as a rolled I beam, is reinforced by two supporting members H, one adjacent each end of the girder. Each support H is attached to the main vertical web of the girder A to which it pertains, intermediate the center of the girder and the corresponding end of the latter. The supports H are not parallel to the girders A, but each extends at an angle away from the girder A to which it is attached, and the attachment to the girder is made in such manner that the support acts on the

vertical web of the girder along all or the major portion of the vertical depth of said web. The outer ends of the supports H are attached through riveted brackets H⁴ to the 5 adjacent ends of the adjacent end frames B.

As shown, each support H comprises a main body portion or part in the form of a channel bar having its parallel edge flanges extending horizontally away from the 10 corresponding girder. Advantageously, as shown, each such channel bar part is connected to the corresponding girder A by a suitable metal plate H' having a portion flat against the vertical web of the girder A 15 and secured to the latter by rivets H², suitably distributed vertically and longitudinally of the girder web. Each plate H' comprises another portion bent away from the girder into parallelism with the corresponding 20 channel bar portion of the support and secured to the vertical web of the latter as by rivets H³. Ordinarily, and as shown, the vertical web of the channel bar portion of each support is less than the vertical 25 depth of the web of the girder A, and each plate H' may well be sheared off to give it the tapered form shown in the drawings. The cage G may be supported in part by one or more hanger bolts G' from the adjacent 30 support H.

With the described arrangement, the supports H offer effective resistance to the tendency of the girders A to be twisted or horizontally deflected by the torsional and deflecting 35 stresses to which they are subjected by the operation of the bridge drive, by the eccentrically disposed load carried by the girders, and by the inertia and momentum effects resulting from the relatively rapid 40 starting and stopping of the crane movements along supports D. Furthermore, the supports H give the girders A additional static load carrying strength by increasing the resistance against any tendency of the 45 top or compression flange of each girder A to buckle sideways under its load.

The crane bridge construction illustrated and described is obviously simple and effective, and the reinforcement of the main 50 girders A in the manner described, has been found in practice to permit those girders to be formed of simple rolled bars under conditions, as to girder length and load supported, which have heretofore made it essential to employ composite or box girders. The use of the invention thus materially de-

creases the weight and construction cost of travelling crane bridges.

While in accordance with the provisions of the statutes I have illustrated and described the best form of my invention now known to me, it will be apparent to those skilled in the art that changes may be made in the form of the apparatus disclosed without departing from the spirit of the invention as 60 set forth in the appended claims, and that certain features of the invention may sometimes be employed without a corresponding use of other features.

Having now described my invention, what 70 I claim as new and desire to secure by Letters Patent, is:

1. The combination in a travelling crane bridge comprising an end frame and a girder connected at one end to said end frame and 75 having a vertical girder reinforcement attached to the web of the girder at vertical points located at a distance from said end frame, said reinforcement extending diagonally away from the girder into engagement 80 with the end frame and being attached to the latter.

2. The combination in a travelling crane bridge comprising an end frame and a girder connected at one end to said end frame and 85 formed with a vertical web, of a girder reinforcement comprising a plate having a portion connected to a portion of said web intermediate the ends of the girder at points distributed longitudinally and vertically of 90 the girder intermediate the ends of the latter, and said plate having a second portion extending diagonally away from the girder, and means connecting said plate and end frame.

3. A travelling crane bridge comprising end frames, a pair of spaced apart parallel girders connecting said end frames and each formed of a rolled metal part having a vertical web and flanges at the upper and lower 100 edges of the latter, and supports attached to said webs or flanges intermediate the ends of the girders and extending diagonally away from the girders into engagement with the end frames, whereby said girders are 105 strengthened against stresses tending to twist or horizontally deflect them.

Signed at Montour Falls, in the county of Schuyler, and State of New York, this 12th day of September A. D. 1927.

JAMES A. SHEPARD.
